UNITED STATES PATENT OFFICE.

HIRAM PERCY MAXIM AND HARRY M. POPE, OF HARTFORD, CONNECTICUT,
ASSIGNORS, BY MESNE ASSIGNMENTS, TO THE COLUMBIA AND ELECTRIC
VEHICLE COMPANY, OF JERSEY CITY, NEW JERSEY.

DESIGN FOR A VEHICLE-FRAME.

SPECIFICATION forming part of Design No. 31,449, dated August 22, 1899.

Application filed July 26, 1898. Serial No. 686,949. Term of patent 14 years.

To all whom it may concern:

Be it known that we, HIRAM PERCY MAXIM and HARRY M. POPE, citizens of the United States, residing in the city and county of Hartford, State of Connecticut, have invented and produced a certain new and original Design for Vehicle-Frames, of which the following is a specification, reference being had to the accompanying drawings, forming a part thereof.

This invention relates to frames for vehicles; and it consists in the design for such frames shown in the accompanying drawings, in which—

Figure 1 is a front end view of a vehicle-frame which embodies the design. Fig. 2 is a rear end view of the same, and Fig. 3 is a plan view of the same.

In accordance with the invention the frame comprises in its design a middle longitudinal vertical member A and across the bottom of

the same horizontal members B, so that when viewed from either end the said members together present the appearance of an inverted-T shape. Oblique members C extend downwardly and outwardly from the stem of the T to its arms.

The characteristic feature of the design is the inverted-T-shaped arrangement of the middle and horizontal members, as seen in end view, with the oblique members from the stem of the T to its arms.

We claim as our invention—

The design for a vehicle-frame, substantially as shown and described.

This specification signed and witnessed this 28th day of June, A. D. 1898.

HIRAM PERCY MAXIM.
HARRY M. POPE.

In presence of—

H. E. HART,
W. B. GREELEY.
